[57] CLAIM

The ornamental design for a magnetic head eraser, as shown.

DESCRIPTION

FIG. 1 is a top plan view of a magnetic head eraser, showing my new design;

FIG. 2 is a rear view of the magnetic head eraser;

FIG. 3 is a front view of the magnetic head eraser;

FIG. 4 is a bottom view of the magnetic head eraser;

FIG. 5 is a right view of the magnetic head eraser which is the same as the left view of the magnetic head eraser;

FIG. 6 is a cross sectional view taken along the vertical center line of FIG. 1;

FIG. 7 is a perspective view of the magnetic head eraser; and

FIG. 8 is an enlarged fragmentary perspective view of the magnetic head eraser.
